UNITED STATES PATENT OFFICE.

RICHARD KOHN, OF NEW YORK, N. Y., ASSIGNOR TO MANHATTAN GLASS PERCOLATOR CO., OF NEW YORK, N. Y., A FIRM.

DESIGN FOR A HOLDER FOR GLASS PERCOLATORS.

48,942.

Specification for Design.

Patented Apr. 25, 1916.

Application filed January 21, 1916. Serial No. 73,479. Term of patent 7 years.

To all whom it may concern:

Be it known that I, RICHARD KOHN, a citizen of the United States, and a resident of the city of New York, borough of Brooklyn, in the county of Kings and State of New York, have invented a new, original, and ornamental Design for a Holder for Glass Percolators, of which the following is a specification, reference being had to the accompanying drawing, forming a part thereof.

The figure is a side elevation of a holder for glass percolators showing my new design.

I claim:

The ornamental design for a holder for a glass percolator, as shown.

RICHARD KOHN.

Witnesses:

WILLARD VEIT,
JULIUS KOHN.
